(57) **CLAIM**

The ornamental design for a watch strap as shown and described.

DESCRIPTION

FIG. 1 is a front side perspective view of a watch strap, showing my new design;

FIG. 2 is a front view of the case accessory of FIG. 1;

FIG. 3 is a back view of the case accessory of FIG. 1;

FIG. 4 is a first side view of the case accessory of FIG. 1; FIG. 5 is a second side view of the case accessory of FIG. 1;

FIG. 6 is a third side view of the case accessory of FIG. 1; and,

FIG. 7 is a fourth side view of the case accessory of FIG. 1. The broken lines are for illustrating portions of the watch strap which form no part of the claimed design.

1 Claim, 7 Drawing Sheets(56)
